Specification for Design.

Patented May 4, 1920.

Application filed August 19, 1919. Serial No. 318,607. Term of patent 3½ years.

To all whom it may concern:

Be it known that I, JULIUS D. BENVENUTI, a citizen of the United States, residing at San Francisco, in the county of San Francisco and State of California, have invented a new, original, and ornamental Design for a Doll, of which the following is a specification, reference being had to the accompanying drawing, forming part thereof.

The figure is a front view of a doll, showing my new design.

I claim:

The ornamental design for a doll, as shown.

JULIUS D. BENVENUTI.
